UNITED STATES PATENT OFFICE

WARREN McARTHUR, JR., OF PHOENIX, ARIZONA

DESIGN FOR A CHAIR

Application filed August 12, 1930. Serial No. 36,641. Term of patent 14 years.

To all whom it may concern:

Be it known that I, WARREN McARTHUR, Jr., a citizen of the United States, residing at Phoenix, county of Maricopa, State of Arizona, have invented a new, original, and ornamental Design for Chair, of which the following is a specification, reference being had to the accompanying drawing, forming a part hereof.

Fig. 1 is a perspective view of the chair showing my new design.

Fig. 2 is an enlarged view showing in elevation a detail feature of the chair.

I claim:

The ornamental design for a chair as shown and described.

WARREN McARTHUR, JR.
